R. THORNTON.

LOOM BEAM.

APPLICATION FILED NOV. 24, 1920.

Patented Oct. 3, 1922.

Inventor:

Ray Thornton
by Frank Woodworth
Atty.

UNITED STATES PATENT OFFICE.

RAY THORNTON, OF NEW BEDFORD, MASSACHUSETTS.

LOOM BEAM.

Application filed November 24, 1920. Serial No. 426,146.

To all whom it may concern:

Be it known that I, RAY THORNTON, a citizen of the United States, and a resident of New Bedford, in the county of Bristol and State of Massachusetts, have invented a new and useful Improvement in Loom Beams, of which the following is a specification.

My invention relates to loom beams upon which the warp threads are wound and from which they are supplied to the loom during the process of weaving, and its object is to provide a simple and convenient means whereby the degree of restraint to which the threads are subjected as they are unwound from the loom beam may readily be changed in accordance with the requirements of the work without substituting one beam-head for another.

Heretofore loom beam heads have been formed integral with pulleys of different sizes over which a belt or chain having one end fixed and the other weighted, is passed. In order to vary the restraint to which the threads are subjected during the winding operation, as when there is a change in the material to be woven the amount of weight suspended on the loose end of the brake band is changed. Sometimes however it is impossible to put sufficient weight on the brake band for a pulley of a given size to secure the requisite degree of restraint. In such cases it is necessary to remove the head with its attached friction device and replace the same by another head having a pulley of different width or diameter.

By means of my invention different degrees of restraint may be put upon the thread by the simple expedient of removing one pulley and replacing the same with another of different width or diameter.

My invention, comprises, essentially, a beam-head and a friction device, such as a pulley, which is removable from, and independent of, said head, together with means whereby it may readily be removed from, and attached to, said head without removing such head from, or disturbing its attachment to the barrel.

An illustrative embodiment of my invention is shown in the drawings which accompany and form a part of this specification, in which--

Figure 1 is a longitudinal section of one end of a loom beam embodying my inven-

tion. Fig. 2 is a transverse section taken on the line 2—2 of Fig. 1, and Fig. 3 is an end view.

In the particular drawings selected for more fully disclosing the principle of my invention, 10 represents the barrel which may be of any suitable construction and to each end of which is attached a head 11, preferably built up of a plurality of layers of wood, each consisting of several bands as described in my Patent No. 1,239,744, dated September 11, 1917, although, of course, it will be understood that I do not limit myself in this particular, inasmuch as heads of any suitable construction may be employed. The heads are fixedly secured to the barrel by bolts 12, herein shown as three in number, the inner end of each of which is threaded to a nut 13 embedded in a slot in the barrel, such slot being closed by a plug 14. The outer end of each bolt passes through and projects from the head, and nuts 15 threaded thereto engage the outer face of the head, thereby tightly clamping the latter against the barrel.

A pulley 16 having its inner face counter-bored to receive the nuts 15 is held against the outer face of one of the heads 11 by means of nuts 17, threaded to the outer ends of the bolts 12.

Preferably the end of each bolt is provided with a kerf 18 to facilitate the screwing of the same into its co-operating nut 13 and the head, if of the type herein shown, preferably is provided with a metallic rim 19 to bind the layers of wood together at their outer edges. The outer face of the pulley may be provided with a rib 20 for engagement with the finger whereby the loom beam is rotated about its axle 21. It will be understood, however, that any suitable means may be employed both for detachably securing the pulley or other friction device to the loom beam and for co-operation with the actuating member.

Over the pulley is passed a belt 22, one end of which is fixed and the other weighted, for the purpose of placing the necessary restraint upon the threads during the process of weaving.

When the nature of the work requires a change in the amount of restraint placed on the threads as they are unwound, the friction device may be easily removed and

another friction device of different diameter or peripheral surface substituted therefor without taking the head off the barrel.

Having thus described an illustrative embodiment of my invention, without however, limiting the same thereto, what I claim and desire to secure by Letters Patent is—

A loom beam comprising a barrel, a head secured to one end thereof, bolts passing through said head and into said barrel, nuts embedded in said barrel and having

threaded engagement with said bolts, respectively, nuts threaded to said bolts respectively and engaging the outer face of said head, a pulley having its inner face resting against said head, and nuts threaded to said bolts and engaging the outer face of said pulley.

In testimony whereof, I have hereunto subscribed my name this 22nd day of November, 1920.

RAY THORNTON.
